ATTORNEY.

UNITED STATES PATENT OFFICE.

HOWARD W. POTTS, OF SAN FRANCISCO, CALIFORNIA.

COLLAR BAND.

Application filed May 31, 1927. Serial No. 195,213.

The present invention relates to an improvement in collar bands for shirts wherein the collar is detachably secured thereto.

The invention has for its objects, to provide a collar band, which, due to its construction prevents the front and rear collar buttons from coming into contact with the neck of the wearer; one wherein the front and rear collar buttons are permanently attached to the collar band, and one wherein said buttons are constructed of rubber or other yieldable material so that the band may be laundered without necessitating the removing of the collar buttons from the collar band, or injuring the collar buttons or shirt-band by the buttons remaining therein.

With the above mentioned and other objects in view, the invention consists in the novel construction and combination of parts hereinafter described, illustrated in the accompanying drawings, and set forth in the claim hereto appended, it being understood that various changes in the form, proportion, size and minor details of construction within the scope of the claim may be resorted to without departing from the spirit or sacrificing any of the advantages of the invention.

In order to more fully comprehend the invention, reference is directed to the accompanying drawings, wherein:—

Fig. 1 is a view in perspective of the collar band and buttons in an assembled position.

Fig. 2 is an enlarged detailed view of one end of the band provided with overlying flaps, showing the base of the front collar button secured to the under flap.

Fig. 3 is a view in cross section taken on line 3—3 of Fig. 1.

Fig. 4 is an enlarged detailed view of one end of the band provided with overlying flaps showing the flaps stitched along their top and end edges, affording a pocket for the base of the collar button.

In the drawings wherein like characters of reference designate corresponding parts, the numeral 1 indicates a conventional collar band. One end 3 of the band 1 is provided with a plurality of separate superimposed flaps 4 and 5, said flap 5 overlying the flap

4 as shown in Fig. 3. A collar button 6 of rubber or other flexible material is attached, at its base 5', to the forward face of the lower flap 4, preferably by being sewed thereto, as shown at 6'. In the pocket 5² in the rear portion of the collar band 1 is positioned a collar button similar to the button 6 and the same is attached to the face of the rear wall of the pocket by sewing, as shown in the dotted lines, Fig. 1 of the drawing. The buttons when so attached becomes substantially integral with the band, as shown in Figs. 1 and 2. By constructing the buttons of flexible material, the laundering of the collar will not be interfered with, nor will the button be likely to become broken from the process of laundering. The flap 5 is provided with a buttonhole 7 for receiving the shank 8 and head 9 of the collar button 6, thus holding the same in position should the flap 4 be moved from its normally flat position, or if, for any reason, the collar button becomes loosened from said flap.

The other end 10 of the band 1 is provided with a buttonhole 11 adapted to receive the head and shank of the collar button, thus detachably securing the two ends of the band when said button is inserted within said buttonhole 11.

It is to be understood that if desired, the flaps 4 and 5 may be stitched along their top and end edges having the bottom of said flaps unstitched affording a pocket for the base of the button, as shown in Fig. 4, thus holding the lower flap 4 against movement. This may be done before or after the front collar button 6 has been attached to the forward face of the flap 4. However, the flaps need not be stitched but may be separate, as shown in Figures 2 and 3 of the drawings.

I claim:—

A collar band provided at one of its ends with a plurality of separate flaps overlying one another, the forward flap provided with a button hole, said flaps secured together at their ends and along their top edge forming a pocket open along its bottom edge, a rubber collar button positioned within the pocket and provided with a head and shank projecting outwardly through the button hole, the other

end of said band provided with a button hole for receiving the head and shank of said button for detachably securing the ends of said collar band together, said button provided with a rubber base provided with a plurality of apertures, stitching securing the base of the button to the forward face of the

rear flap through said apertures, said open bottom edge of the pocket affording means for inverting the pocket for the securing of 10 the button base to the rear flap.

In testimony whereof I have signed my name to this specification.

HOWARD W. POTTS.
